(57) **CLAIM**

The ornamental design for a vehicle light cluster, as shown and described.

DESCRIPTION

FIG. 1 is a front perspective view of a preferred embodiment of the vehicle light cluster according to the present design; FIG. 2 is a rear elevational view of the vehicle light cluster of FIG. 1;

FIG. 3 is a left-side elevational view of the vehicle light cluster of FIG. 1, the right-side elevational view being a mirror image thereof;

FIG. 4 is a front elevational view of the vehicle light cluster of FIG. 1; and,

FIG. 5 is a top plan view of the vehicle light cluster of FIG. 1, the bottom plan view being a mirror image thereof.
